UNITED STATES PATENT OFFICE.

JOHN SCHNEIDER, OF ELIZABETH, NEW JERSEY.

INSULATOR-CLAMP.

1,334,802.

Specification of Letters Patent. Patented Mar. 23, 1920.

Application filed April 22, 1919. Serial No. 291,872.

To all whom it may concern:

Be it known that I, JOHN SCHNEIDER, a citizen of the United States, and a resident of Elizabeth, county of Union, and State of New Jersey, have invented a new and Improved Insulator-Clamp, of which the following is a full, clear, and exact description.

This invention relates to insulator clamps, and more particularly to an adapter clamp for use in connection with insulators.

An object of this invention is to provide the design of an insulator clamp which may be clamped upon the head of the standard and conventional type of insulators in present day use on high tension electrical transmission lines.

Particularly, an object of this invention is to provide an insulator clamp which will in effect function as an adapter to be mounted upon the uppermost head of a standard insulator for the purpose of holding in position electrical transmission conductors or wires carried by the insulator.

Another object of this invention is to provide an insulator clamp which will adapt itself to the head of variously shaped insulators, and more particularly an insulator clamp which may be conveniently and quickly installed upon insulators even though the insulators vary in their circumferential proportions.

With the above and other objects in view the invention has relation to a certain combination and arrangement of parts, an example of which is described in the following specification, pointed out in the appended claims, and illustrated in the accompanying drawings, wherein:

Figure 1 shows a plan view of the insulator clamp.

Fig. 2 shows the insulator clamp in elevation with a portion thereof broken away, and parts of the clamp shown in dotted lines.

Fig. 3 also shows the clamp in elevation with the parts thereof broken away to illustrate the form of adapter cap used in connection with the insulator clamp.

Fig. 4 shows a clamp leg separately from the assembled device.

Referring now more in particular to the drawings, the numeral 1 points out a base member with a substantially rectangular shape. At each corner of the base a pair of

extended ears 2 are formed integrally with the base member, and are spaced in parallel relationship one with the other, thus forming an opening in which a clamp leg is pivotally mounted. The outer wall base of the material, bounded between the parallel walls of the extended ears, is designated by the reference character 2^a. This face or surface 2^a is arcuate in contour forming a cam shaped face, the function of which will hereinafter be disclosed.

The aforesaid clamp leg is designated by the reference numeral 3, and is pivotally mounted between the extended ears on a pin 4. A bolt or rivet may be employed for pivoting the clamp leg in position, preferably a rivet will be used to obtain a better, lasting and more permanent job. The upper end of the clamp leg is provided with a bore which receives a cap screw 5 so arranged as to have its forward rounded end positioned in pressure contact against the wall of the cam face 2^a. The lower portion of the clamp leg is provided with a spreading arm 6 which has an interior arcuate contour adapted to fit the cylindrical form of the insulator head upon which the clamp is mounted.

The arcuate face of the clamp leg is further illustrated in Fig. 4 and designated by the numeral 7. In manufacturing this form of insulator clamp the inner contacting face 7 of the clamp leg will have a circumferential design adapted to fit the style of insulator for which the clamp is manufactured. The cap screw carried by the clamp leg will be tightened up against the cam face 2^a of the clamp base member 1 thus pressing the face 7 of the clamp leg into pressure contact with the head of the insulator.

The insulator is designated by the reference character A in the drawings, and the insulator is usually formed with an upper rim B which leaves a grooved portion between the upper rim B and the body A of the insulator. The insulator clamp is designed to be fitted to the groove and thus securely held in position on the insulator.

The description has directly related to one clamping member of the base, but it is understood that the base member will be fitted with any appropriate number of the clamp sets as is illustrated in the drawings. Usually four equi-distantly spaced clamp sets will be employed on the base member.

This design so spaces the clamp sets as to be opposite one another and oppose each other in their clamping relation thus effectively distributing the strain throughout the structure and through the head of the insulator.

- A boss 9 is integrally formed upon the upper portion of the base and provided with an adapter cap 10. The boss and cap will 10 preferably be rectangular in design, and provided with adjacent grooved channels 11 of suitable diameter to carry high tension transmission cables or wires C. The adapter cap is provided with cap screws 12 which 15 pass through bores therein and screw-thread into tapped bores within the base. Thus the adapter cap acts to hold cables or wires in a clamped relation upon the base of the insulator clamp.
- 20 This formation of adapters may be employed in connection with the disclosed form of insulator clamp. In Fig. 3 is shown a slightly modified form of adapter which is designed to carry a single cable. It may also be desirable to employ an adapter cap or fitting to be connected with a suspending link, or connected with some form of pipe fitting to hold the insulator clamp suspended from a ceiling or spaced outwardly from a wall.
- 25 Many different designs of adapter caps can 30 obviously be employed for use in connection with this form of insulator clamp.

In many cases it is necessary to employ two or more insulators where high tension 35 transmission lines are lead over railroad tracks and other places. This kind of installation usually requires the use of several insulators and obviously several insulator clamps. It is the usual practice to space the 40 insulators apart one from the other, and this is done by employing a spacer rod or link placed between the individual insulators. Rods or links may be bolted or otherwise secured to the base of this clamp for spacing 45 them apart in rigid relationship.

In mounting this insulator clamp upon insulators the cap screws carried by all the clamp legs will be loosened up thus causing the legs to be spaced in their outwardly disposed position. The clamp will then be applied to the neck or groove of the insulator just under the rim thereof and the cap screws tightened up which closes the arcuate clamping legs inwardly against the cylindrical face of the insulator. In some cases it may be desirable to use a piece of fiber or other thin sheet material to form a better seating position for the clamp against the insulator.

50 It quite often happens that the circumferential proportions of insulators vary. This is occasioned by the process of manufacture which causes the molded or cast insulator material to become slightly distorted thus 55 when the insulator is turned out of a factory

as a finished product it may be slightly oblong in form instead of cylindrical. This insulator clamp may be fitted upon the distorted and shapeless forms of insulators to the same effect and advantage as it may be 70 installed upon perfectly shaped insulators. The invention is presented as covering a form of insulator clamp which will fill a long-felt want in the erection of high tension 75 transmission lines and other electrical undertakings.

Having thus described my invention, what I claim as new and desire to secure by Letters Patent is:

1. An insulator clamp comprising, a base 80 member, extended ears integrally formed with the base member, a clamp leg pivoted between the ears, and a screw carried by the clamp leg for moving said leg into a clamping position with any object upon 85 which the insulator clamp may be installed.

2. An insulator clamp comprising, a base member, extended ears integrally formed with the base member, a clamp leg pivoted between the ears, and a screw carried by the 90 clamp leg for moving said leg into a clamping position with any object upon which the insulator clamp may be installed, and an adapter cap employed on the base for pivoting electric conductor cables. 95

3. An insulator clamp comprising, a base, ears integrally formed therewith and arranged in pairs, clamp legs pivotally confined between the ears constituting a pair, a cam face formed on the base member adjacent the clamp leg, and a cap screw carried by the clamp leg for compressively engaging the cam to move the clamp leg into clamping engagement with an insulator. 100

4. An insulator clamp comprising, a base, 105 ears integrally formed therewith and arranged in pairs, clamp legs pivotally confined between the ears constituting a pair, a cam face formed on the base member adjacent the clamp leg, and a cap screw carried by the clamp leg for compressively engaging the cam to move the clamp leg into 110 clamping engagement with an insulator, and an adapter attachment employed in connection with the base for holding electric wires. 115

5. An insulator clamp comprising, a base, ears provided on the base, clamp legs pivotally carried by the ears, an arcuate face formed at the base of the clamp legs, and a 120 screw carried by each clamp leg to engage the arcuate face to force said clamp legs into a permanently clamped position upon any object adapted to receive the insulator clamp. 125

6. An insulator clamp comprising, a base, ears integrally formed on the base and projecting from the perimeter thereof, a rocker arm clamp pivotally mounted on the ears, and means related with the rocker arm 130

clamps for driving the rocker arms in clamped relation against any object upon which the insulator clamp is mounted.

7. An insulator clamp comprising, a base, 5 ears provided therein, clamps pivotally carried by the ears, arcuate faces formed on the base, and a screw employed for moving the clamp into contacting position with any object upon which the insulator clamp is 10 mounted, and an adapter cap fitted to the upper portion of the base.

8. An insulator clamp in the form of an

adapter to carry electric transmission cables over an insulator, said adapter comprising, a base, ears integrally formed with the base 15 and projecting from the perimeter thereof, a device pivoted between the ears, said base having a cam formed thereon at the junction of the ears and between the ears, means associated with the device to engage the cam 20 and thrust the device in clamped position against the insulator upon which the adapter is mounted.

JOHN SCHNEIDER.
